(57) **CLAIM**

The ornamental design for a bracket light, as shown and described.

DESCRIPTION

FIG. 1 is a perspective view of a first embodiment of the bracket light showing my new design.

FIG. 2 is a rear perspective view of a first embodiment of the bracket light.

FIG. 3 is a front view of a first embodiment of the bracket light.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is an enlarged view of a portion indicated with “9” in FIG. 1.

FIG. 10 is an enlarged view of a portion indicated with “10” in FIG. 1.

FIG. 11 is an enlarged view of a portion indicated with “11” in FIG. 2.

FIG. 12 is a perspective view of a second embodiment of the bracket light.

FIG. 13 is a rear perspective view of a second embodiment of the bracket light.

FIG. 14 is a front view of a second embodiment of the bracket light.

FIG. 15 is a rear view of FIG. 14.

FIG. 16 is a left side view of FIG. 14.

FIG. 17 is a right side view of FIG. 14.

FIG. 18 is a top view of FIG. 14.

FIG. 19 is a bottom view of FIG. 14; and,

FIG. 20 is an enlarged view of a portion indicated with “20” in FIG. 13.

The dash-dot-dash broken lines show the boundaries of the enlarged views and form no part of the claim thereof.

1 Claim, 20 Drawing Sheets
